DESIGN FOR CARPET.

Specification forming part of Design No. 6,713, dated June 24, 1873; application filed June 6, 1873.

To all whom it may concern:

Be it known that I, ALFRED HEALD, of the city and county of Philadelphia, State of Pennsylvania, have invented a Design for a Carpet-Pattern, (A,) of which the following is a specification:

The nature of my design is fully represented by the figure in the accompanying drawing, which shows all the features of the pattern, the remainder being merely a repetition of that which appears.

The pattern is of a foliated character, and consists, principally, of a series of vines or stems, A, each arranged in the form of a scroll, inclosing a trefoil, B, and ornamented by ten-

drils and bunches of leaves a. The spaces between the several scrolls or stems A are occupied by ornaments D of the character represented.

Irrespective of the colors employed, I claim—

The design for a carpet-pattern, substantially as described, and as represented in and by the accompanying drawing.

In testimony whereof I have signed my name to this specification in the presence of two subscribing witnesses.

ALFRED HEALD.
